CONTAINER CLOSURE

Semon H. Stupakoff, Pittsburgh, Pa.

Application September 12, 1935, Serial No. 40,299

11 Claims. (Cl. 215—8)

My invention relates generally to a new and useful improvement in container closures and more particularly to an improved stopper or closure for use in bottles and like receptacles by means of which the re-use of the bottle may be readily detected.

One of the objects of my invention is to provide a novel construction for a bottle or receptacle closure, having displaceable elements or parts, which will clearly reveal whether or not the contents of the bottle have been partially or wholly removed or whether an attempt has been made to tamper with the contents. It is herein represented as applied to a bottle.

My invention further relates to means whereby the displaced elements of the closure may not be restored to their original positions after the closure has been attached to the receptacle and the displaceable portions released to permit access to the contents of the receptacle.

My invention also contemplates provision of a sealing groove between the neck of the bottle and the closure, so that when the closure is secured in place by means of cement any excess cement will be displaced into the groove and thereby prevented from flowing or oozing into the bottle.

In the accompanying drawing, illustrating the present preferred embodiment of my invention and in which like numerals are employed to designate corresponding parts throughout the same,

Figure 1 represents a sectional view showing the closure in position in the neck of a bottle,

Figure 1A is a sectional view of a portion of the top of the neck of the bottle and the closure on a scale larger than the scale in Figure 1,

Figure 2 is a view in general similar to Figure 1, showing the displaceable portions of the closure immediately after displacement,

Figure 3 is a plan view along the line III—III of Figure 1,

Figure 4 is a view partly in section of the assembled stopper,

Figures 5 and 6 are views in elevation of various parts of the closure,

Figures 7 and 8 are inverted plan views of Figures 5 and 6, respectively,

Figure 9 shows a modification of my invention,

Figure 10 shows a further modification of my invention,

Figure 11 is a plan view of a detailed part of Figure 10, and

Figure 12 shows another modification of my invention.

In the drawing, 1 designates the neck of a bot-

tle or other suitable receptacle in which a stopper or closure 2 of suitable size, made according to my invention, is inserted. In Figure 1, a screw cap 3 is shown, which engages with the external threads 4 on the bottle neck. Between the cap 5 and the stopper a gasket 5 of suitable material is placed. Formed on the upper portion of the bottle neck 1 is a seat or shoulder 6.

The stopper 2 comprises a liner member and closing plugs, and may or may not have a sealing 10 gasket. The liner member or bushing 7 is of a suitable size to fit into the open end of the bottle neck 1 and has an inclined opening 8 in the top thereof which terminates in an inwardly projecting annular lip 9. The bushing may be made of 15 any material which will not adversely affect or be affected by the contents of the bottle. I prefer to use a material which is easily and readily moldable, such as glass, ceramic material, or moldable plastic. The bushing or liner member 7 is pro-

vided at its lower end with an internal thread 10. Inserted into the bushing from the bottom is a plug or releasing element 11 of approximately 20 the same outside diameter as the inside diameter of bushing 7. The plug 11 has an annular flange 25 or shoulder portion 12 which engages the annular lip 8 of the liner member to limit the outward movement of the plug and which prevents the plug from being inserted from the top of the bushing. The plug or releasing element 11 (see 30 Figures 5 and 7) has one or more ratchet-like projections or teeth 13 on its lower surface, and its opposite end or upper surface has a cross-slot 14 of suitable size to be readily engaged by a coin.

Screwed into the bottom of bushing 7 is a threaded plug or releasable element 15 (see Figures 6 and 8). This plug has one or more ratchet-like 35 portions or teeth 16 on its upper face adapted to engage the teeth 13 on plug 11. On the lower face of plug 15 a cross-slot 17 of suitable size is 40 provided for enabling the member 15 to be readily turned in assembling the stopper. Plug 15 has an external thread 18 thereon which is adapted to cooperate with internal thread 10 of bushing 7. The pitch of these threads preferably is such that 45 the plug 15 need only be turned through not more than 360° to insert or remove it from the bushing 7. Plug 15 can be made from any suitable material as aforementioned in connection with the description of plug 11.

The seat or shoulder 6 of bottle neck 1 has an annular groove or depression 19 therein. This groove is of importance when the closure or stopper 3 is cemented in place in the bottle neck. As the stopper fits as closely as economical manu-

facturing conditions will permit, it is difficult to accurately gauge and apply the correct amount of cement to properly seal the stopper in the bottle. The groove 19 is designed to receive any 5 excess cement and prevent it from running or oozing into the bottle.

The stopper is assembled before being put in the bottle by placing plug 11 on plug 15 so that the ratchet teeth engage. The plugs are then 10 inserted in bushing 7 and screwed up to the position shown in Figure 4, so that the shoulder 12 of plug 11 is in contact with annular lip 9 of the bushing 7. The assembled stopper, as shown in Figure 4, is then placed in position in the neck 15 of the previously filled bottle and cemented in place by use of a cement which is so adherent that the stopper cannot be removed without destruction of the bottle neck or the closure.

To gain access to the contents of the bottle, 20 after removal of the cap 3 and gasket 5, a coin or other convenient article, is inserted in the cross-slot 14 of plug 11 and turned in the direction to unscrew plug 15 from the liner member 7. Plugs 11 and 15 will then both drop down into 25 the bottle, as shown in Figure 2, and the contents of the bottle may be poured out. It is impossible to insert new plugs in the bushing 7 from the top and impossible to re-set plugs 11 and 15 which have fallen into the bottle. One 30 attempting to re-set plugs 11 and 15 would have to hold the filled bottle upside down and manipulate the loose plugs until plug 11 fell into bushing 7 and then further manipulate the bottle until plug 15 engaged the threads in the lower 35 portion of bushing 7. Even were this accomplished, it would be impossible to screw plug 15 into operative position in the bushing because the direction of the ratchet teeth on both plugs is such that they cooperate only when turning 40 in one direction and in that direction, the plugs are loosened and not tightened. If the bottle is refilled and any other stopper is used, the presence of plugs 11 and 15 in the bottle immediately reveals that the bottle has been re-used.

45 The modification shown in Figure 9 is similar to the arrangement already described, except that the bottle is shown without having external threads on the neck and a portion of the bottle neck has an unstanding lip 2a which surrounds 50 the upper portion of the stopper. Between the shoulder 12 of plug 7 and the annular lip 9, a gasket 20 is interposed. This arrangement will provide a thorough seal for the contents of the bottle independently of a screw cap or other 55 device. Of course, if desired, a similar gasket could also be used in the arrangement illustrated in Figures 1, 1A, and 2. In all other respects the stopper illustrated is identical in construction with that which has already been described.

60 In the modification shown in Figure 10, the neck of the bottle and the outside of the liner 7a have cooperating straight sides and a groove 21 is formed in the inside of the neck 2a and a groove 22 is formed on the outside of the liner 65 7a. The arrangement of the stopper is alike in all other particulars and when assembled, and just before the stopper is inserted in the neck, a retaining ring 23, shown in detail in Figure 11, is compressed in groove 22, and, when the stopper is placed in position in the neck, the ring will 70 expand part way into groove 21 and this will securely lock the stopper against removal. The ring 23 may conveniently be formed of resilient metal.

75 In the structure shown in Figure 12, the re-

leasable element or plug 24 is a dish-shaped member having internal threads 25 and ratchet-like projections or teeth 16a, which teeth are similar in form and function to teeth 16 already described in connection with plug 15 and 5 illustrated in Figures 6 and 8. The liner member 1b has a depending portion 7c with external threads which engage with threads 25 on plug 24. In all other respects, the arrangement and construction of this stopper is the same as that 10 which has already been described.

I have shown and specifically described certain present preferred embodiments of my invention, but it will be understood that the invention may be otherwise constructed and embodied within the scope of the following claims. It will be further understood that the modifications shown in the different figures may be variously combined, for example, the gasket shown in Figure 9 could be included in a modification 20 similar to Figure 1, or a gasket could be interposed in Figure 12 between plug 24 and portion 7c of liner 1b. Various other combinations will readily occur to one skilled in the art.

I claim:

1. A container stopper comprising a liner member adapted to be irremovably secured in the container opening and having a passageway therethrough, a releasable element for said passageway and so positioned that when it is released it falls into the container, separate means wholly within the liner member above the releasable element for operating the releasable element to release it, and retainers on the liner and the releasable element, operating means for preventing withdrawal of said last mentioned means when positioned in the liner member above the releasable element.

2. A closure for a container having a relatively restricted opening therethrough, comprising a 40 bushing seated in said opening, a plug having threaded engagement with the inner end of the bushing, and a separate releaser in the bushing accessible from the exterior of the container for unscrewing said plug, inter-engaging connections between the bushing and the releaser to prevent outward removal of the releaser, having driving coaction with said plug in the unscrewing direction only.

3. A closure for a container having a relatively 50 restricted opening therethrough, comprising a bushing seated in said opening, a plug having threaded engagement with the inner end of the bushing, and a separate releaser in the bushing accessible from the exterior of the container for unscrewing said plug, inter-engaging connections between the bushing and the releaser to prevent outward removal of the releaser, having driving coaction with said plug in the unscrewing direction only and being free to drop by gravity into 60 the container after said plug has been unscrewed.

4. A closure for a container having a relatively restricted opening therethrough, comprising a bushing seated in said opening, a plug having threaded engagement with the inner end of the bushing, and a separate releaser accessible from the exterior of the container for unscrewing said plug, said releaser having driving coaction with said plug in the unscrewing direction only, inter-engaging connections between the bushing and the releaser to prevent the outward removal of the releaser from the bushing, said plug and said releaser being insertable in the bushing only from the inside end of the bushing.

5. A container stopper comprising a liner mem-

ber having a passageway therethrough, said passageway having an internally threaded portion, a releasable element for said passageway having a threaded portion for cooperation with the threaded passageway, a separate releaser accessible from the exterior of the container for turning said element in one direction only when in position in the passageway, and inter-engaging connections between the liner member and releaser to prevent the outward removal of the releaser from the liner.

6. A container stopper comprising a liner member having a passageway therethrough and an externally threaded portion, a releasable element for said passageway having a threaded portion for cooperating with the threaded liner member, a separate releaser accessible from the exterior of the container for unscrewing said releasable element, said releaser having driving coaction with the releasable element in the unscrewing direction only, and inter-engaging connections between the liner member and releaser to prevent the outward removal of the releaser from the liner.

7. A closure for a container having a relatively restricted opening therethrough, comprising a bushing seated in said opening, a plug having threaded engagement with the inner end of the bushing, a separate releaser accessible from the exterior of the container for unscrewing said plug, said releaser having driving coaction with said plug in the unscrewing direction only, and inter-engaging connections between the bushing and the releaser for preventing withdrawal of said releaser from the outside of the container.

8. A closure for a container having a relatively restricted opening therethrough, comprising a bushing seated in said opening, a plug having threaded engagement with the inner end of the bushing, a separate releaser accessible from the exterior of the container for unscrewing said plug, said releaser having driving coaction with said plug in the unscrewing direction only, inter-engaging connections between the bushing and

the releaser for preventing withdrawal of said releaser from the outside of the container, said bushing being cemented to said container, and means for preventing the cementing material from oozing into the bottle.

9. A container stopper comprising a liner adapted to be irremovably secured in the container opening and having a passage therethrough, a releasable closure element for said passageway, a separate releaser for said element in the liner above said element, and inter-engaging connections between the releaser and the liner arranged to prevent removal of the releaser outwardly through the liner, said releasable element and the releaser being free to drop into the container when the releasable element is released.

10. A container stopper comprising a liner adapted to be irremovably secured in the container opening and having a passage therethrough, a releasable closure element for said passageway, a separate releaser for said element in the liner supported on said element, inter-engaging connections between the releaser and the liner arranged to prevent removal of the releaser outwardly through the liner, said releasable element and the releaser being free to drop into the container when the releasable element is released, and means for irremovably securing the liner to the container.

11. A container stopper comprising a liner adapted to be irremovably secured in the container opening and having a passage therethrough, a releasable closure element for said passageway, a separate releaser for said element in the liner above said element, inter-engaging connections between the releaser and the liner arranged to prevent removal of the releaser outwardly through the liner, said releasable element and the releaser being free to drop into the container when the releasable element is released, and means between the releaser and the liner to prevent leakage of the container contents.

SEMON H. STUPAKOFF.
